DESIGN FOR A BONBON-DISH.

No. 37,726.

Specification for Design.

Patented Dec. 12, 1905.

Application filed October 19, 1905. Serial No. 283,554. Term of patent 14 years.

To all whom it may concern:

Be it known that I, CHARLES A. BENNETT, a citizen of the United States, residing at Taunton, in the State of Massachusetts, have invented a new, original, and ornamental Design for Bonbon-Dishes, of which the following is a specification, reference being had to the accompanying drawing, forming a part thereof.

The figure is a plan view of a bonbon-dish, showing my new design.

I claim—

The ornamental design for a bonbon-dish, as shown.

CHARLES A. BENNETT.

In presence of—

GEORGE E. CHAMBERS,
HERBERT O. WOOLLEY.
